Plagwitz, Germany, assignors to Gebrüder
Brehmer, Leipzig-Plagwitz, Germany, a firm of
Germany

Application October 13, 1930, Serial No. 488,460
In Germany July 24, 1930

13 Claims. (Cl. 270—53)

The present invention relates to book-stitching machines and more particularly concerns a method for opening the signatures fed to such machines by an automatic sheet feed.

5 Usually, in this type of machine, the closed book sections or signatures are fed to suitable opening means whereby each signature is placed straddlewise upon a sheet carrier which then positions the signature beneath the stitcher head. 10 Signatures are comparatively easy to open and handle in this fashion, provided that they are folded in such a manner that the halves fit and are held one into the other, as is the case when a sheet is both parallel folded and cross folded.

15 It is common in the art, however, for the signatures to be formed by parallel folding only, and also for signatures that have been so formed, or cross folded, as the case may be, to be provided with front or end sheets which are separately attached thereto.

20 When the signature to be handled is formed as last described or provided with attached end sheets, difficulty is experienced in opening and positioning the signature upon the sheet-carrier, by any of the known methods. The inner sheets or leaves not held by the suction members tend to move away from the correct middle fold and so become unevenly divided when placed upon the sheet carrier.

25 The object of this invention is to provide a convenient method of opening such signatures and placing them, accurately divided along the middle fold, upon the sheet-carrier.

30 According to this invention cross currents of air are directed over the apex of the sheet-carrier to impinge upon the inner leaves of a signature during the passage of the latter between rotary suction members.

35 One embodiment of this invention is shown in the accompanying drawings, applied to signature opening apparatus of the inversely rotating suction-roll type, in which:

40 Fig. 1 is an elevational view of a rotary sheet-carrier stitching machine of well known type shown fitted with a sheet opening device according to this invention.

45 Fig. 2 is a fragmentary detail view drawn to a larger scale of a unit of the sheet opening apparatus.

50 Fig. 3 is a view taken at right angles to Fig. 2.

55 Referring to Fig. 1 of the drawings, the machine comprises a frame 15 in which are mounted upon a vertical shaft 16 the rotary sheet carrier arms 11. The latter serve to carry sheets or signatures S and are rotated by mechanism which imparts

a rise and fall motion to the arms and supporting shaft during the said rotation. The mechanism for this purpose together with the manner of its operation is very well known in the art and will not be further described in this connection since it forms no part of the present invention.

5 Positioned above the path of travel of the rotary sheet-carriers 11 is the sheet opening device with which this invention is more particularly concerned.

10 The device comprises inversely rotating suction rolls 10 mounted on stub shafts journaled in brackets 17 depending from the machine frame 15 and provided with automatically controlled suction orifices 12 (Figs. 2 and 3).

15 The suction orifices 12 are formed in the circumferential faces of the rolls 10 and each orifice communicates by means of a right angle passage 12a (Fig. 3) with a corresponding orifice on one lateral face of the said roll. Valve plates 10a sup-

20 ported by the brackets 17 are adapted resiliently to engage the apertured lateral faces of the rolls 10 and are connected to a suitable suction pump through the conduits indicated by the reference

25 23. Obviously, when the lateral orifices register with the valve plates 10a, suction is created in the corresponding circumferential orifices whereupon a signature leaf contacting therewith is caused to adhere to the suction roll.

30 When the orifices, during the rotation of the rolls 10, move clear of the corresponding valve plates the vacuum created by the suction is destroyed and the signature released from the rolls 10 and so dropped upon the carrier arm positioned to receive it.

35 35 Conveyor belt pulleys 18 and 19 journaled in the machine frame, together with a belt tensioning pulley 20 journaled in a bracket pivotally mounted on the machine frame, are associated with the suction rolls 10 and serve to carry conveyor belts 21 which also pass around the suction rolls 10 and feed thereto the signatures S.

40 The conveyor belts are driven by a driving belt 21a extending from a driving pulley 21b.

45 A sheet supporting or lay table 22 is utilized to support the sheets or signatures to be fed to the conveyor belts.

50 Air nozzles or blowers 13, 13' are positioned adjacent the suction rolls 10 so as to be offset from the path of the sheet carriers 11 as shown in Fig. 3 and at the same time obliquely positioned as shown in Figs. 1 and 2 in order to direct cross currents of air over the apex of each sheet carrier when the latter is positioned beneath the sheet opening device to receive a signature opened 55.

and released therefrom. The currents of air so directed cross above the sheet carrier and impinge upon the members 10 or sheets about to be placed straddlewise upon the members 11.

5 5 The air nozzles or blowers 13, 13' are mounted on flexible air conduits 24 (Fig. 1) which are secured to a stand pipe 25 connected to a suitable air pump 26. Air is thus supplied to the nozzles 13, 13' and the position of the latter may readily be adjusted by bending as desired the flexible conduits 24.

10 The above set forth apparatus is also disclosed in our co-pending application Serial No. 489,220, filed October 16, 1930.

15 In operation, the closed signature is fed, by hand or automatically, to the conveyor belts 21 and so to the inversely rotating suction members 10. During the travel of the signature between these members, the outside sheets thereof are seized by the applied suction and opened by the rotation of the members 10 as shown in Fig. 2.

20 25 When the signatures consist of parallel folded or cut sheets or are provided with front or end sheets 14, as above described and shown in Fig. 2, the inner sheets or pages of the signature, so opened, are not under the direct control of the suction members. That is to say, the inner leaves or sheets being unsecured at their outer edges to the outside sheets, tend to resist the opening pull 30 of the members 10 and are separated from the outer sheets by the slight tension exerted by the middle fold of the signature.

35 35 The cross currents of air, however, impinge upon these inner sheets as the signature is opened and so press the leaves of the divided signature towards their respective divisions. The signature is thus held open and correctly divided until deposited upon the sheet-carrier by the automatic suction release as above described.

40 45 Such blower attachments may be employed singly, if cross-folded signatures having only one attached sheet are to be opened, or may be provided in pairs as above described or series of pairs, when cross-folded signatures having attached front and end sheets, or parallel folded signatures with or without attached sheets are to be opened.

50 55 Provision may also be made to control individually the air supply to each pair of blower attachments so as to enable each one to be operated separately and to this end control cocks 27 are fitted to the T branch of the stand pipe 25. In this manner when opening a cross-folded signature having an attached front sheet, the rear blower attachment only would be operated, and when opening a similarly folded signature having an attached back or end sheet the front attachment only would be operated. It would, of course, be possible, by the same controlling means, to cut off the blast completely 60 when a cross-folded sheet without attached end sheets was to be opened by the mechanism.

65 70 It will be appreciated that the above described method of opening signatures is applicable to any type of book stitching machine in which automatic signature-opening apparatus is employed such as, for instance, rotary-arm thread-stitching machines, book-stitching machines employing reciprocating carriers and also known types of wire-stitching machines.

75 We claim:

1. A signature-opening device for use in a signature-handling machine, comprising, in combination, at least one pair of inversely rotatable suction rolls, each provided with an opening in

its circumferential face communicating with an opening in a lateral face thereof, said circumferential face also having an annular groove formed therein, conveyor belts arranged to travel in said grooves so that adjacent stretches of said belts cooperate to feed closed signatures between the circumferential faces of said rolls, an arcuate valve plate associated with each roll and arranged to register intermittently with the opening in said lateral face, means for connecting said valve plates to a source of vacuum so that the limbs of the signatures passing between said rolls are seized, parted and released, and means for directing at least one current of air upon the inner leaves of the opened signature to hold them apart. 15

2. A signature-opening device for use in a signature-handling machine, comprising, in combination, at least one pair of inversely rotatable suction rolls, each provided with an opening in its circumferential face communicating with an opening in a lateral face thereof, said circumferential face also having an annular groove formed therein, conveyor belts arranged to travel in said grooves so that adjacent stretches of said belts cooperate to feed closed signatures between the circumferential faces of said rolls, an arcuate valve plate associated with each roll and arranged to register intermittently with the opening in said lateral face, means for connecting said valve plates to a source of vacuum, so that the limbs of the signatures passing between said rolls are seized, parted and released, and at least one nozzle arranged to impinge a current of air upon the inner leaves of the opened signature. 35

3. A signature-opening device for use in a signature-handling machine, comprising, in combination, at least one pair of inversely rotatable suction rolls, each provided with an opening in its circumferential face communicating with an opening in a lateral face thereof, said circumferential face also having an annular groove formed therein, conveyor belts arranged to travel in said grooves so that adjacent stretches of said belts cooperate to feed closed signatures between the circumferential faces of said rolls, an arcuate valve plate associated with each roll and arranged to register intermittently with the opening in said lateral face, means for connecting said valve plates to a source of vacuum so that the limbs of the signatures passing between said rolls are seized, parted and released, and a plurality of nozzles arranged to impinge currents of air upon the inner leaves of the opened signatures. 40

4. A signature-opening device for use in a signature-handling machine, comprising, in combination, at least one pair of inversely rotatable suction rolls, each provided with an opening in its circumferential face communicating with an opening in a lateral face thereof, said circumferential face also having an annular groove formed therein, conveyor belts arranged to travel in said grooves so that adjacent stretches of said belts cooperate to feed closed signatures between the circumferential faces of said rolls, an arcuate valve plate associated with each roll and arranged to register intermittently with the opening in said lateral face, means for connecting said valve plates to a source of vacuum so that the limbs of the signatures passing between said rolls are seized, parted and released, and a plurality of nozzles arranged to impinge currents of air upon the inner leaves of the opened signatures. 45

5. A signature-opening device for use in a sig- 55

- 5 nature-handling machine, comprising, in combination, at least one pair of inversely rotatable suction rolls, each provided with an opening in its circumferential face communicating with an opening in a lateral face thereof, said circumferential face also having an annular groove formed therein, conveyor belts arranged to travel in said grooves so that adjacent stretches of said belts cooperate to feed closed signatures between the circumferential faces of said rolls, an arcuate valve plate associated with each roll and arranged to register intermittently with the opening in said lateral face, means for connecting said valve plates to a source of vacuum so that the limbs of the signatures passing between said rolls are seized, parted and released, and a plurality of nozzles arranged to direct currents of air over the apex of said carrier and upon the inner leaves of the opened signature to hold them apart prior to seating the signature upon said carrier. 10
- 10 6. In a signature-handling machine, in combination, a movable, roof-shaped signature carrier and means for depositing an opened, folded signature straddlewise upon said carrier, including at least one pair of inversely rotatable suction rolls positioned above said carrier, each roll being provided with an opening in its circumferential face communicating with an opening in a lateral face thereof, said circumferential face also having an annular groove formed therein, conveyor belts arranged to travel in said grooves so that adjacent stretches of said belts cooperate to feed closed signatures between the circumferential faces of said rolls, an arcuate valve plate associated with each roll and arranged to register intermittently with the opening in said lateral face, means for connecting said valve plates to a source of vacuum so that the limbs of the signatures passing between said rolls are seized, parted and released, and at least one pair of nozzles arranged in opposition to impinge cross currents of air upon the inner leaves of the opened signatures. 15
- 15 7. In a signature-handling machine, in combination, a movable, roof-shaped signature carrier and means for depositing an opened, folded signature straddlewise upon said carrier, including at least one pair of inversely rotatable suction rolls positioned above said carrier, each roll being provided with an opening in its circumferential face communicating with an opening in a lateral face thereof, said circumferential face also having an annular groove formed therein, conveyor belts arranged to travel in said grooves so that adjacent stretches of said belts cooperate to feed closed signatures between the circumferential faces of said rolls, an arcuate valve plate associated with each roll and arranged to register intermittently with the opening in said lateral face, means for connecting said valve plates to a source of vacuum so that the limbs of the signatures passing between said rolls are seized, parted and released, and means for directing at least one current of air over the apex of said carrier and upon the inner leaves of the opened signature to hold them apart prior to seating said signature upon said carrier. 20
- 20 8. In a signature-handling machine, in combination, a movable, roof-shaped signature carrier and means for depositing an opened, folded signature straddlewise upon said carrier, including at least one pair of inversely rotatable suction rolls positioned above said carrier, each roll being provided with an opening in its circumferential face communicating with an opening in a lateral face thereof, said circumferential face also having an annular groove formed therein, conveyor belts arranged to travel in said grooves so that adjacent stretches of said belts cooperate to feed closed signatures between the circumferential faces of said rolls, an arcuate valve plate associated with each roll and arranged to register intermittently with the opening in said lateral face, means for connecting said valve plates to a source of vacuum so that the limbs of the signatures passing between said rolls are seized, parted and released, and at least one pair of nozzles arranged on either side of said movable carrier and offset from the path of movement thereof, said nozzles being arranged in opposition to impinge cross currents of air upon the inner leaves of the opened signature to hold them apart prior to seating said signature upon said carrier. 25
- 25 9. In a signature-handling machine, in combination, a movable, roof-shaped signature carrier and means for depositing an opened, folded signature straddlewise upon said carrier, including at least one pair of inversely rotatable suction rolls positioned above said carrier, each roll being provided with an opening in its circumferential face communicating with an opening in a lateral face thereof, said circumferential face also having an annular groove formed therein, conveyor belts arranged to travel in said grooves so that adjacent stretches of said belts cooperate to feed closed signatures between the circumferential faces of said rolls, an arcuate valve plate associated with each roll and arranged to register intermittently with the opening in said lateral face, means for connecting said valve plates to a source of vacuum so that the limbs of the signatures passing between said rolls are seized, parted and released, and at least one pair of nozzles arranged on either side of said movable carrier and offset from the path of movement thereof, said nozzles being arranged in opposition to impinge cross currents of air upon the inner leaves of the opened signature to hold them apart prior to seating said signature upon said carrier. 30
- 30 10. A signature-opening device for use in a signature-handling machine, comprising, in combination, a pair of bearing brackets, a pair of shafts journaled in said brackets, at least one pair of inversely rotatable suction rolls mounted upon said shafts, said rolls each being provided with at least one opening in its circumferential face with an opening in a lateral face thereof, oppositely disposed sleeve members secured to said bearing brackets, arcuate valve plates supported by said sleeve members so as to press resiliently against the apertured lateral faces of said rolls, and register intermittently with the openings in said lateral face, means for connecting a source of vacuum to said valve plates so that the limbs of signatures passed between said rolls are seized, parted and released, and means for impinging at least one current of air upon the inner leaves of the opened signature to hold them apart. 35
- 35 11. A signature-opening device for use in a signature-handling machine, comprising, in combination, a pair of bearing brackets, a pair of shafts journaled in said brackets, at least one pair of inversely rotatable suction rolls mounted upon said shafts, said rolls each being provided with at least one opening in its circumferential face with an opening in a lateral face thereof, oppositely disposed sleeve members secured to said bearing brackets, arcuate valve plates supported by said sleeve members so as to press resiliently against the apertured lateral faces of said rolls. 40
- 40

- 5 said rolls and register intermittently with the openings in said lateral face, means for connecting a source of vacuum to said valve plates so that the limbs of signatures passed between said rolls are seized, parted and released, and at least one nozzle arranged to impinge a current of air upon the inner leaves of the opened signature.
- 10 12. A signature-opening device for use in a signature-handling machine, comprising, in combination, a pair of bearing brackets, a pair of shafts journalled in said brackets, at least one pair of inversely rotatable suction rolls mounted upon said shafts, said rolls each being provided with at least one opening in its circumferential face with an opening in a lateral face thereof, 15 oppositely disposed sleeve members secured to said bearing brackets, arcuate valve plates supported by said sleeve members so as to press resiliently against the apertured lateral faces of said rolls and register intermittently with the opening in said lateral faces, means for connecting a source of vacuum to said valve plates so that the limbs of signatures passed between said rolls are seized, parted and released, and a plurality of nozzles arranged to impinge currents
- 20

of air upon the inner leaves of the opened signatures.

13. A signature-opening device for use in a signature-handling machine, comprising, in combination, a pair of bearing brackets, a pair of shafts journalled in said brackets, at least one pair of inversely rotatable suction rolls mounted upon said shafts, said rolls each being provided with at least one opening in its circumferential face with an opening in a lateral face thereof, 5 oppositely disposed sleeve members secured to said bearing brackets, arcuate valve plates supported by said sleeve members so as to press resiliently against the apertured lateral faces of said rolls and register intermittently with the opening in said lateral faces, means for connecting a source of vacuum to said valve plates so that the limbs of signatures passed between said rolls are seized, parted and released, and at least one pair of nozzles arranged in opposition to 10 impinge cross currents of air upon the inner leaves of the opened signatures.
